UNITED STATES PATENT OFFICE.

FRANK JONES, OF SALT LAKE CITY, UTAH.

BEET SCREENING, PILING, AND LOADING MACHINE.

1,336,297.

Specification of Letters Patent.

Patented Apr. 6, 1920.

Application filed August 19, 1919. Serial No. 318,453.

To all whom it may concern:

Be it known that I, FRANK JONES, a citizen of the United States, residing at Salt Lake City, in the county of Salt Lake and 5 State of Utah, have invented certain new and useful Improvements in Beet Screening, Piling, and Loading Machines, of which the following is a specification.

My invention relates to certain new and 10 useful improvements in combined machines having means for receiving beets, or material to be handled from a wagon or other conveyance; means for screening out or separating the dirt or other foreign matter 15 from the beets and determining the amount of said dirt; and means for subsequently piling the clean beets, or material and loading the same onto a conveyance, or depositing the cleaned material at a point of 20 deposit.

A leading object of the present invention is to construct a machine of the type mentioned having instrumentalities for carrying out the several operations in a rapid, continuous and satisfactory manner, and with 25 this end and other objects in view my invention consists of the parts and the constructions, arrangements and combinations of parts as I will hereinafter describe and point 30 out in the appended claims.

A further object of my invention is to construct a single, compact, portable machine of the tractor type, having means for receiving beets or other material directly and from a 35 conveyance on the ground, and after weighing. The gross contents of the conveyance is elevated and screened and the dirt from the beets dumped is returned to the conveyance and its amount determined, while the 40 cleaned beets are elevated and conveyed to a pile or to cars, said machine being equipped with the necessary mechanical parts for propelling the machine over the ground and for actuating the conveying and other mechanisms, as I will hereinafter describe.

In the accompanying drawings forming part of this specification and wherein similar reference characters indicate like parts in the several views:

50 Figure 1 is an end elevation of a combined loading and unloading machine embodying my invention.

Fig. 2 is a side elevation of the same.

55 Fig. 3 is a top plan view showing the trommel or screen and portions of the conveyers broken away.

While the machine I am about to describe in more or less detail will be found useful in the handling, screening and storing of different kinds of material, I have designed it 60 primarily to operate upon sugar or other beets; in other words, for the purpose of dumping the beets from a conveyance, located on the ground, into a series of hoppers which feed the beets to appropriate conveyers, 65 which latter are designed to elevate the beets and the associated dirt and other foreign material, to a relatively flat conveyer which transports the beets and dumps them into a trommel, or rotary cylindrical screen. During 70 the conveying operation through this screen, the dirt which is associated with the beets is screened out or separated from the beets and the separated dirt or foreign material, is conveyed to a hopper having, if desired, 75 a controlling discharge gate or valve.

The cleaned beets from the trommel are designed to be elevated to a pile or loaded into cars by means of a suitable conveyer.

In said drawings, I have illustrated in 80 Fig. 1, a conveyance which may be of any suitable character, the body *a*, thereof being shown in its dumping position. From the conveyance *a* the beets or other material drop into a series of hoppers *b* herein shown 85 as three in number (Fig. 3) the conveyance being tilted a little at a time to properly feed the beets so that they will not spill over the sides of the conveyer with which the hoppers communicate; this tilting of the 90 conveyance may be effected by any suitable means and for this purpose I have shown a pair of pulley-blocks *c*, attached to a crane *d* of suitable construction, as shown in Fig. 1, and a hauling-line *e*, which is rove through 95 the pulleys and has its free end suitably connected to a winch or winding drum, *f*, on a transverse shaft *m*. To operate this shaft, a chain drive may be employed and to this end I show a chain running from the upper 100 sprocket wheel *i* of the tail pulley of the horizontal or flat conveyer, *h*, which I will hereinafter describe, to a lower sprocket wheel *j*, on the shaft of which is a worm *k*, which engages a worm-wheel *l* on the shaft *m*, said 105 shaft and winch carrying the members of a suitable clutch *n*, which controls the motion of the winch. Any desired accessories of the usual type may be employed in connection with these features.

110 From the hoppers, *b*, the beets dropped thereinto from the conveyance *a* fall upon

suitably placed endless conveyers o , one under each hopper, which conveyers may be of the usual or well known flat type and pass over the head and tail pulleys, r and q , respectively, said conveyers being driven by chain drives s (Fig. 3), which drive a sprocket wheel t ; the chain drives themselves are driven by sprocket wheels u , on the shaft v .

10 From the three conveyers o , the beets or other material being handled, drop onto a flat conveyer, h , which runs substantially horizontally at right-angles to the travel of the conveyers, o , (Fig. 2) or crosswise of the 15 discharge end of the conveyers, o , said flat conveyer being of the endless type and passing over a head pulley w , driven by a chain drive w ; the lower sprocket wheel y of this chain drive is mounted on the shaft z , while 20 the upper sprocket wheel a' is on the shaft b' which also carries the head pulley w .

At the head end of the horizontal conveyer h is disposed a chute c' , into which the conveyer delivers and from the chute the beets 25 are directed into a trommel d' . This so-called trommel is in fact a rotary cylindrical screen of suitable form and construction, set at a suitable incline, Fig. 2, and adapted to screen out or separate the associated dirt from 30 the beets, the beets, representing the oversize of the material under treatment, being delivered from the lower end of the trommel, and the dirt, representing the undersize of said material, being received into an underlying hopper e' . In practice the trommel 35 comprises an annular series of parallel pipes or rods suitably spaced apart and so arranged that as the beets are caused to roll around or to be agitated the adhering dirt is loosened or broken away and falls through 40 the spaces between the parallel pipes or rods and is received into the hopper e' and thence is directed upon a trough conveyer p' .

The trommel, or rotary cylindrical screen, 45 d' , is operatively mounted on pairs of rollers, g' , at the head and tail ends, which rollers are fast on shafts, h' , which are revolved by chain drives i' j' . The lower sprocket wheel k' of the chain drive i' is fast to the 50 main line shaft l' , and the upper sprocket wheel m' is made fast to the shaft h' . The chain drive j' runs over the sprocket wheels n' and o' , which are fast on the roller-shaft h' , Fig. 2.

55 The dirt which is screened from the beets falls, as before stated, into the hopper e' and is thence directed upon the trough conveyer, p' , having head pulley q' , and tail pulley v' . This trough conveyer is actuated 60 by the chain drive r' passing around the upper sprocket s' , fast to the shaft t' , of the head pulley, and the lower sprocket u' , which is fast on the main line shaft l' . The dirt received onto the trough conveyer is elevated and drops from the conveyer onto a

70 hopper w' , from which it is drawn into the conveyance a , (Figs. 1 and 3) after the latter has been discharged or dumped of its load of beets and has been moved ahead underneath the said hopper. From the hopper 75 the conveyance with the dirt which has been screened from its original load of beets, is taken to suitable scales and weighed so as to determine the net weight of the original load of beets.

75 The trommel, or rotary cylindrical screen is hinged at one end and may have its inclination adjusted or altered at will by means of a jack or screw x' (Fig. 2) to thereby regulate the speed at which the beets will 80 travel through the trommel, and a small conveyer, y' is suitably disposed to drag the dirt which passes through the sides of the trommel and lodges on the extended bottom, z' of the trommel, so that said dirt will be 85 emptied on to the trough conveyer, p' . The drag conveyers y' travel over sprocket wheels, $c c'$ on the shafts D, D' , said shaft D being driven by a chain drive E which passes over a sprocket wheel, F , on the shaft 90 D and is driven from a sprocket G on the shaft H of the tail pulley I of the said trough conveyer.

95 The trough conveyer p' is operated by a chain drive k which runs over a sprocket wheel, I , fixed to the shaft of the head pulley M ; the lower sprocket wheel N of the chain drive K , is fastened to the shaft b' and revolves therewith.

100 The chain drive x operates the shaft b' and on this shaft is the upper sprocket wheel, d' , a corresponding lower sprocket wheel, y , being mounted on the shaft z , which is driven by a pair of miter-gears $T U$, the latter being fixed to the shaft v . Another 105 gear wheel V is fastened to the said shaft v and is driven by a pinion W on the main line shaft l' . It will be understood that in its operation the trough conveyer elevates the 110 cleaned beets and deposits them into a suitable receiver; for instance, into railroad cars. The machine, I have described, is propelled by its own engine, A^2 , (Fig. 3) which may be of any approved type and the shaft of 115 which carries a pinion B^2 , which meshes with and drives a gear wheel, C^2 , on the shaft, D^2 , said shaft carrying a sprocket wheel, F^2 from which a chain E^2 extends to a lower sprocket wheel G^2 on the main line shaft l' . This or equivalent mechanism is 120 employed for transmitting the power of the engine to operate the mechanisms described.

125 The machine has a main frame, H^2 , of appropriate character and material and which may include pairs of channel irons placed back to back, as shown in Fig. 1, and which are mounted on an I-beam and support the hoppers, b . The main frame is supported by two pairs of wheeled trucks, J^2 , K^2 , the wheels, L^2, M^2 , of which are shown 130

under the hoppers *b*. This main frame is hinged at the points, *Z*, (Fig. 2) so as to be detachable and the two parts made readily portable.

5 The conveyer frames before described are hung to the main frame *H²* by angle irons or equivalent structures.

The frame of the trough conveyer, *p'*, is of any desired construction and is hinged 10 to the main frame at the points, *Y*, and is supported near one end by the wheels, *O²* and is detachable at the hinges *Y*, so that it can readily be separated for transportation purposes. The hopper and head pulley of 15 this trough conveyer are also suitably supported. Suitable supporting agencies are also provided for the flat conveyer, *h*. The trommel or rotary cylindrical screen, *d'* is supported by beams running lengthwise and cross-wise; the lengthwise extending beams are hinged at the lower end *P²*, to the main frame of the machine while the other and upper end of the 20 trommel is connected to the elevating screw *x'*, before described.

The frame of the trough conveyer, *f'*, is of suitable construction and is supported by the main frame, which also supports a cantaliver frame, *Q²*, (Fig. 2) to which the upper part of the conveyer frame is attached. The two idlers, *R²* (Fig. 2) which carry the chain drive for the trough conveyer are supported on the main frame by a channel iron or other support, *R³*.

35 From the foregoing description it will be understood that the machine shown has the necessary equipment to dump and receive the contents of a conveyance and to convey and elevate the same, and separate the dirt 40 from the beets; that the oversize, represented by the cleaned beets is conveyed and elevated into a suitable receiver, and that the undersize from the screen representing the dirt, is caught by a conveyer and delivered 45 into a hopper and finally sent back into the conveyance from which the beets were originally received, and its amount quickly ascertained.

The machine carries its own motive power 50 and the entire operation is continuous. The machine is portable and flexible and can be moved from place to place so that it will pile beets, or other material, into any size pile that a given area will permit; it can also be 55 drawn alongside a string of cars and load them without the necessity of moving the cars.

Having thus described my invention what I claim as new and desire to secure by Letters Patent is:—

60 1. A machine of the character described, having a main frame; a compartment hopper supported on said frame; a series of parallel inclined conveyers, said hopper overlying the receiving ends of said conveyers

and having each of its compartments communicating with one of the conveyers; a conveyer extending substantially at right-angles to the first-named conveyers and cross-wise of the discharge ends thereof; a 70 screen in line with and receiving material from said cross-conveyer; a third conveyer extending parallel with the said series of conveyers and substantially at right-angles to the cross-conveyer and screen, and receiving the undersize from the latter; a conveyer substantially in line with the cross conveyer and screen and succeeding the latter and receiving the oversize therefrom, and means for operating said conveyers. 75 80

2. A machine of the character described having in combination, a main frame; a right-angled extension of one end thereof; a series of endless conveyers operating in said extension; a receiver disposed adjacent 85 the lower end of said conveyers; a hoisting mechanism supported on the conveyer frame adapted to tilt a conveyance to cause the same to discharge into said receiver; a conveyer above and extending in the direction of the major portion of the main frame, said conveyer operating cross-wise of the upper ends of the series of conveyers; a screening-appliance in line with the cross-conveyer and arranged proximate to the delivery end thereof adapted to receive material therefrom; a third conveyer succeeding the delivery end of the screening-appliance 90 95 and extending lengthwise of the major portion of the main frame adapted to receive the oversize from the screen and to transfer the same to a distant point; and a conveyer underlying the screening-appliance extending at substantially right-angles thereto and parallel with the series of conveyers, and adapted to receive the undersize of material from the screening appliance, said last-named conveyer adapted to transport the undersize to a point adjacent the receiving end of the machine whereby it 100 105 110 may be delivered back into said conveyance.

3. A machine of the character described having in combination, a main frame; a right-angled extension of one end thereof; a series of endless conveyers operating in said extension; a receiver disposed adjacent the lower end of said conveyers; a hoisting mechanism supported on the conveyer frame adapted to tilt a conveyance to cause the same to discharge into said receiver; a conveyer above and extending in the direction of the major portion of the main frame, said conveyer operating cross-wise of the upper ends of the series of conveyers; a screening appliance in line with the cross-conveyer and arranged proximate to the delivery end thereof adapted to receive material therefrom; a third conveyer succeeding the delivery end of the screening appliance and extending lengthwise of the major portion 115 120 125 130

of the main frame adapted to receive the oversize from the screen and to transfer the same to a distant point; and a conveyer underlying the screening-appliance extending 5 at substantially right-angles thereto and parallel with the series of conveyers and adapted to receive the undersize of material from the screening-appliance, said last-named conveyer adapted to transport the undersize to 10 a point adjacent the receiving end of the machine whereby it may be delivered back into said conveyance; said main frame having a cantaliver extension upon which the discharge end of the third named conveyer 15 is supported; means for varying the inclination of the screening-appliance, and a chute at the delivery end of the cross-wise operating conveyer and into which the undersize from the screening-appliance is delivered for discharge into said conveyance. 20

4. A machine of the character described having a main frame; a compartment hopper supported on said frame; a series of parallel inclined conveyers, said hopper 25 overlying the receiving ends of said conveyers and having each of its compartments communicating with one of the conveyers; a conveyer extending substantially at right-angles to said series of conveyers and cross- 30 wise of the discharge ends thereof; a rotary cylindrical screen in line with and receiving material from said cross-wise conveyer; a third conveyer extending parallel with the said series of conveyers and substantially 35 at right-angles to the cross-conveyer and screen, and receiving the undersize from the latter; a conveyer substantially in line with the cross conveyer and screen and succeeding the latter and receiving the oversize 40 therefrom, said main frame having a side extension at one end upon which the series of conveyers and hopper are supported; means mounted on said extension for operating the series of conveyers and the undersize 45 conveyer, and the rotary screen; and a power mechanism on the machine adapted to propel said machine.

5. A machine of the character described having in combination, a main frame and a 50 lateral extension thereof at one end; a plurality of receiving hoppers supported on said extension and extending cross-wise thereof; a series of inclined conveyers supported on said extension having their lower 55 or receiving ends disposed beneath said hoppers; a framework supported on said extension and hoisting appliances mounted therein adapted to tilt a conveyance so that it will discharge into said hoppers; a substantially horizontal conveyer operating 60 cross-wise of the upper delivery ends of said series of conveyers adapted to receive material therefrom; a rotary inclined trommel or screen having an inlet positioned to receive

material delivered from the second named 65 conveyer; separate conveyers for the undersize and oversize of the material delivered from the screen or trommel, said undersize conveyer leading upwardly and backwardly to the receiving end of the machine; 70 and a hopper at the receiving end of the machine beneath the delivery end of the undersize conveyer adapted to deposit the undersize into said conveyance.

6. A machine of the character described 75 having in combination, a main frame, said frame having a side extension at one end; wheeled trucks for the main frame and extension; a series of inclined parallel conveyers mounted in said extension of the main 80 frame; a compartment hopper extending cross-wise of the lower ends of said series of conveyers; a crane supported on said extension; hoisting devices mounted thereon adapted to engage and tilt a conveyance so 85 that it will discharge into the several compartments of the hopper; a substantially horizontal conveyer operating cross-wise of the delivery ends of the series of conveyers; an inclined rotary screen in line with said cross-wise operating conveyer and receiving material therefrom, said screen being 90 pivotally mounted at one end and having means at the opposite end for varying its inclination; a hopper underlying the screen 95 adapted to receive the undersize of material delivered therefrom; an inclined conveyer having its lower end underlying said hopper, said conveyer leading backwardly and upwardly in the direction of the frame extension to the receiving end of the machine; an upwardly inclined conveyer for receiving the oversize from the screen and conducting it to a distant point; means for propelling said machine; and complementary 100 means for transmitting power to the various conveyers.

7. In a machine of the character described, a rotary inclined screen; means for delivering material into said screen; a hopper underlying said screen adapted to receive the undersize therefrom; a main frame upon which the screen is adjustably supported; an upwardly inclined conveyer operating substantially at right angles to the axis of 115 the screen having its lower end underlying the hopper, said hopper having an extended floor; a drag-belt operating over said floor; and an upwardly inclined conveyer extending substantially at right-angles to 120 the first-named conveyer and receiving the oversize from the screen and adapted to conduct the same to a distant point, said frame having a cantaliver extension for supporting the last named conveyer.

In testimony whereof I affix my signature.

FRANK JONES.
